UNITED STATES PATENT OFFICE

JOSEPH BETHENOD, OF PARIS, FRANCE

ELECTRIC ORGAN

Application filed April 22, 1929, Serial No. 357,184, and in France May 10, 1928.

My invention relates to a novel electric instrument or organ, electrically actuated by an arrangement of alternators of musical frequency and of very feeble power, of variable reluctance type, coupled to a telephone loud speaker through a thermionic amplifier.

An object of my invention is to develop this fundamental idea in a particular manner and to disclose embodiments which can be advantageously adopted to obtain an instrument sufficiently simple, robust and at low cost.

My invention will be more fully understood by reference to the annexed drawing which represents an embodiment of an organ according to my invention. Let it be assumed that the problem is to produce either singly or in combination eighty-four different notes representing seven octaves. A motor 5 of any convenient type whose speed is maintained constant by means of the regulator 6, which may be of any familiar type, drives the shaft 7. The latter by means of silent helicoidal gears 8, 8' and 8'', itself drives twelve shafts such as 1, 1' and 1'', etc. A tachometer 9 serves to control the speed of the entire group. On each one of these secondary shafts there is mounted an alternator 10, 10', 10'', the ratios of gears 8, 8' and 8'' being chosen in such manner that the corresponding frequencies shall be those of the scale in which the lowest note is the A of the sub-contra group, corresponding to approximately 27.18 vibrations per second, which is practically the lowest frequency required in music.

Furthermore, on each one of the shafts 1, 1', 1'', there are mounted three other alternators whose frequencies are with reference to those of the first in the ratios 2, 8, 32. All these alternators are of homopolar form having variable reluctance, obtained by rotating an eccentric disc in the field. In some alternators the entire periphery may be occupied by active stator elements, and in other alternators only a fractional part of the periphery, depending on the particular alternator, may be so occupied. Of course the particular numbers mentioned may be modified according to the effects

desired, and the number of secondary shafts and the number of alternators may be chosen as required.

In the circuit of alternator 10 there is connected a line switch 13, an output coil 31, an iron core inductance 14, and a limiting impedance coil 11. The iron core of inductance 14 is movable axially, thus varying the inductance. Key 12 controls the circuit of alternator 10 by closing the line switch 12 and is attached to the iron core of inductance 14 so that depressing key 12 withdraws a part of the iron core from inductance 14. If key 12 is lightly depressed, a note of low intensity is obtained, and as key 12 is depressed further, the note intensity increases. The maximum intensity of each note may be limited by the limiting impedance coil 11 which may be adjusted by the control 15. Provision may be made to change the setting of control 15 while playing.

The alternating current produced by the alternator 10 is transmitted to tuned circuit 17 for generating and controlling harmonics which include variable condensers 18 and 20 and variable self-inductance coil 19. These circuits are coupled to the input coil 21 of a thermionic amplifier 22. The amplified currents are reproduced by loud speakers 23 of an ordinary type, such as moving coil. Trills or analogous effects can be produced by acting periodically on the circuits by means of a rapidly varying impedance such as a rheostat or inductance. The rheostat may have a rotating slider, the inductance coil may be of the variometer type and have a movable rotor, and these may be controlled by hand or foot. The output of alternator 24 whose frequency is double that of the alternator 10 can be delivered to amplifier 22 and loud speakers 23 by depressing key 27 or its output can be delivered to another similar system of amplifiers and loud speakers represented diagrammatically at 29 and 30, by depressing key 28.

According to my invention this second series of loud speakers represented at 30 is of a special type which does not have direct current excitation or any permanent mag-

net and its motor unit reduces to a simple alternating current electromagnet. It is a characteristic of such a loud speaker that it produces for an input frequency f , a musical note of frequency $2f$, an octave above the input frequency. Consequently since loud speakers 23 are of an ordinary type one will obtain, according as one depresses key 27 or 28, either the note corresponding to the frequency of alternator 24, or a note one octave higher. Alternators 25 and 26 are arranged in the same manner as alternator 24 and can thus control as desired either loud speakers 23, or loud speakers 30. It is therefore evident that with the four alternators driven by the shaft 8 one can obtain seven notes which are in the ratios 1, 2, 4, 8, 16, 32, 64, the alternator 10 producing the note 1, the alternator 24 producing the notes in the ratios 2 and 4, the alternator 25 producing the notes in the ratios 8 and 16, and the alternator 26 producing the notes in the ratios 32 and 64. The alternators mounted on the other shafts 1', 1'', are connected to the amplifiers 22 and 29 by connections similar to those connecting the alternators of shaft 1.

There are thus obtained eighty-four notes from forty-eight alternators, while with the arrangements heretofore known it would have been necessary to have eighty-four alternators to obtain the same result. The resulting advantage of the invention is therefore considerable, the great number of alternators heretofore necessary being a serious inconvenience of apparatus heretofore proposed of a similar type.

It is to be understood that the example shown in the drawing is not to be considered a limitation and it is evident that the invention can be easily applied to cases in which the number of musical notes to be produced is different.

What I claim as new and desire to secure by Letters Patent of the United States is as follows:

1. An electric organ comprising in combination a plurality of alternators synchronously driven at constant speed, means for amplifying the currents produced by said alternators, two separate systems of loud speakers adapted to be selectively supplied by said alternators, one of said systems having loud speakers whose motors comprise alternating current electromagnets without continuous current excitation and, without permanent magnets, whereby the number of musical notes obtained is greater than the number of said alternators.

2. In an electric organ, a plurality of alternators of different frequency characteristics driven synchronously at constant speed, thermionic amplifiers for amplifying the output of said alternators, individual line switches for selectively controlling the

output circuits of said alternators, two systems of loud speakers, one of said systems comprising loud speakers delivering a note corresponding to the frequency of the input current of said system, the other of said systems comprising loud speakers driven by an alternating current electromagnet, and means for selectively delivering to said loud speaker systems the outputs of said alternators.

3. In an electric organ, a plurality of alternators of different frequency characteristics driven synchronously at constant speed, thermionic amplifiers for amplifying the output of said alternators, individual line switches for selectively controlling the output circuits of said alternators, two systems of loud speakers, one of said systems comprising loud speakers delivering a note corresponding to the frequency of the input current of said system, the other of said systems comprising loud speakers delivering a note corresponding to twice the frequency of the input current of said system, and means for selectively delivering to said loud speaker systems the outputs of said alternators.

4. In an electric organ, a plurality of alternators of different frequency characteristics driven synchronously at constant speed, thermionic amplifiers for amplifying the output of said alternators, individual line switches for selectively controlling the output circuits of said alternators, two systems of loud speakers, one of said systems comprising loud speakers delivering a note corresponding to the frequency of the input current of said system, the other of said systems comprising loud speakers driven by an alternating current electromagnet, means for selectively delivering to said loud speaker systems the outputs of said alternators, and individual rapidly variable impedances in the output circuit of each of said alternators for varying the output wave form of said alternator.

JOSEPH BETHENOD.
